DESIGN FOR A SHOE

Bernard Oswell, New York, N. Y.

Application February 9, 1937, Serial No. 67,528

Term of patent 3½ years

To all whom it may concern:

Be it known that I, Bernard Oswell, a subject of the King of Great Britain, residing in city, county, and State of New York, have invented a new, original, and ornamental Design for a Shoe, of which the following is a specification, reference being had to the accompanying drawing, forming part thereof,

Fig. 1 is a plan view of a shoe showing my new design.

Fig. 2 is a perspective view of the shoe as shown in Fig. 1.

An essential feature of my invention resides in the placing of jewelled elements of ornamentation on the ankle strap and the vamp straps of the shoe.

I claim:

The ornamental design for a shoe, substantially as shown and described.

BERNARD OSWELL.
